US00D552643S

(12) **United States Design Patent** (10) Patent No.: **US D552,643 S**
Bonomi (45) Date of Patent: **** Oct. 9, 2007**

(54) **ELECTRIC ACTUATOR**

(75) Inventor: **Aldo Bonomi**, Brozzo (IT)

(73) Assignee: **Valbia S.r.l.**, Brozzo (BS) (IT)

(**) Term: **14 Years**

(21) Appl. No.: **29/275,261**

(22) Filed: **Dec. 19, 2006**

(30) **Foreign Application Priority Data**

Jun. 19, 2006 (EM) 000546270-0001

(51) **LOC (8) Cl. 15-99**

(52) **U.S. Cl. D15/199; D15/149**

(58) **Field of Classification Search** D15/149,

D15/199; 74/89.15, 490.09; 310/20, 80

See application file for complete search history.

(57) **CLAIM**

The ornamental design for an electric actuator, substantially, as shown and described.

DESCRIPTION

FIG. 1 shows a perspective view of an electric actuator from the front;

FIG. 2 shows a right side view;

FIG. 3 shows a rear view;

FIG. 4 shows a left side view;

FIG. 5 shows a front view;

FIG. 6 shows a top view; and,

FIG. 7 shows a bottom view;

1 Claim, 4 Drawing Sheets

FIG. 1

FIG. 2

FIG. 3

FIG. 4

FIG. 5

FIG. 6

FIG. 7
